UNITED STATES PATENT OFFICE.

EDWIN A. MERRITT, OF NEW YORK, N. Y., ASSIGNOR TO THE DIAMOND MATCH COMPANY, OF CHICAGO, ILLINOIS, A CORPORATION OF ILLINOIS.

DESIGN FOR A HOLDER FOR BOOK OR CARD MATCHES AND THE LIKE.

46,055.

Specification for Design.

Patented July 7, 1914.

Application filed May 4, 1914. Serial No. 836,374. Term of patent 14 years.

To all whom it may concern:

Be it known that I, EDWIN A. MERRITT, a citizen of the United States, residing in the city and county of New York, State of New York, have invented a new, original, and ornamental Design for Holders for Book or Card Matches and the like, of which the following is a specification, reference being had to the accompanying drawing, forming a part thereof.

In the drawing—Figure 1 is a plan of a book or card match holder showing my new design; Fig. 2 is a front elevation of the holder, and Fig. 3 is an end elevation thereof.

In Figs. 1 and 2 a base for the holder is represented in dotted lines for the purpose of illustrating the relation of the holder to a base, but the shape of the base is not claimed.

I claim—

The ornamental design for a holder for book or card matches and the like substantially as shown.

EDWIN A. MERRITT.
